(57) **CLAIM**

The ornamental design for a railing top rail, as shown and described.

DESCRIPTION

FIG. 1 is a perspective view of our railing top rail; FIG. 2 is an end view thereof; FIG. 3 is a left side view thereof, the right side being a mirror image thereof; FIG. 4 is a top view thereof; and, FIG. 5 is a bottom view thereof. The break lines depict bounds of the claim. The portion between the break lines forms no part of the claimed design.
